[57] CLAIM

The ornamental design for a laundry iron, as shown and described.

DESCRIPTION

FIG. 1 is a top and front perspective view of a laundry iron, showing my new design;

FIG. 2 is a top and rear perspective view thereof;

FIG. 3 is a side elevational view thereof, the side view thereof opposite that shown in FIG. 3 being the mirror image thereof;

FIG. 4 is a top plan view thereof;

FIG. 5 is a bottom plan view thereof;

FIG. 6 is a front elevational view thereof; and,

FIG. 7 is a rear elevational view thereof.
